(Cl. D14—3)

To all whom it may concern:

Be it known that I, Frank P. Fletcher, a citizen of the United States, residing at Pasadena, in the county of Los Angeles and State of California, have invented a new, original, and ornamental Design for a Household Utility Cart, of which the following is a specification, reference being had to the accompanying drawing, forming part thereof, in which:

Fig. 1 is a front elevational view of a household utility cart, showing my new design;

Fig. 2 is a side elevational view;

Fig. 3 is a rear elevational view;

Fig. 4 is a top plan view; and

Fig. 5 is a bottom plan view, thereof.

I claim:

The ornamental design for a household utility cart, as shown.

FRANK P. FLETCHER.
